(57) **CLAIM**

The ornamental design for a harness, as shown and described.

DESCRIPTION

FIG. 1 is a perspective view of the harness according to the present design;

FIG. 2 is a left side view of the harness as shown in FIG. 1;
FIG. 3 is a right side view of the harness as shown in FIG. 1;
FIG. 4 is a top plan view of the harness as shown in FIG. 1;
FIG. 5 is a bottom plan view of the harness as shown in FIG. 1;

FIG. 6 is a front view of the harness as shown in FIG. 1;
FIG. 7 is a rear view of the harness as shown in FIG. 1; and,
FIG. 8 is a environmental view of the harness as shown in FIG. 1.

The features shown in broken lines in FIG. 8 depict portions of the harness that form no part of the claimed design.
